MEANS FOR DRESSING GRINDING WHEELS
USED FOR FORM GRINDINGHerbert Henry Harley and James Yorston,
Coventry, EnglandApplication August 5, 1936, Serial No. 94,432
In Great Britain August 24, 1935

5 Claims. (Cl. 125—11)

This invention relates to an improved method of and means for trueing or dressing grinding wheels used for form-grinding, such for example as are employed in producing or finishing screw-
5 threads, annular ribbed members and the like, and more particularly to grinding wheels in which the operative face is formed with a plurality of annular ribs and grooves.

Broadly stated, there are two methods which 10 can be employed for dressing formed grinding wheels of the kind referred to. In one case the movement of the diamond or the like is obtained by means of mechanism which generates the form required. The other methods involves the 15 use of a former shaped as an enlarged and in some cases modified replica of the form to be produced, a stylus moving in contact with the former being connected with the dressing tool by suitable reduction mechanism.

20 The present invention is concerned with the latter method and has for one of its objects to provide improved means whereby relative movement between the former and stylus or tracer is reproduced on a reduced scale between the dressing tool and the wheel.

25 We are aware that for the purpose of dressing the operative face of a grinding wheel it has already been proposed to employ two compound slides, one carrying the dressing tool and the other the stylus or tracer, in combination with means for causing the two compound slides to move in unison in proportionate relationship.

In the method adopted according to the present invention relative movement between the 30 former and a stylus or tracer co-operating therewith is reproduced at a reduced ratio between the dressing tool and the grinding wheel by means of a combination of rectilinear and rotary motions.

40 The rectilinear and rotary components of the combined movement may correspond respectively with the length and depth of the profile of the former. Both of said components may be reduced to an equal extent at the dressing tool or 45 at the grinding wheel, as the case may be, or the ratio of reduction in the case of one component may be less than in the case of the other component.

According to one construction of wheel dressing 50 apparatus embodying the present invention the stylus, or the former, is carried by a lever pivotally mounted in a sliding saddle so as to have a combined rectilinear and rotary motion, and the dressing tool, or the wheel head, is carried by a compound slide one member of which

is moved in one direction by the rectilinear motion of the saddle while the other member is moved in a different direction by the rotary motion of the lever. Alternatively, the dressing tool, or wheelhead, may also have a combined rectilinear and rotary motion.

In another and simpler form of wheel dressing apparatus embodying this invention there are two slides movably mounted in a common guide, one carrying the lever and the other the former, and means are provided for imparting simultaneous relative movement to the said slides in the guide at a given ratio depending upon the degree of reduction required. In this case the dressing tool is carried direct by the short arm 15 of the lever and the stylus by the long arm, the ratio of the lengths of the two arms being preferably equal to that of the relative movements of the two slides.

In the accompanying drawings,
Figure 1 is a plan view of one form of the improved wheel dressing apparatus.

Figure 2 is a longitudinal vertical sectional view thereof on the line II—II of Figure 1.

Figure 2A is a detailed sectional view on an enlarged scale of part of the apparatus shown in Figure 2.

Figures 3 and 4 are transverse sectional views on the lines III—III and IV—IV respectively of Figure 2.

Figures 5 and 6 are views similar to Figures 1 and 2 respectively showing an alternative construction, Figure 6 being taken on the line VI—VI of Figure 5.

Figures 7 and 8 are cross-sectional views on the lines VII—VII and VIII—VIII respectively of Figure 6.

Figures 9 and 10 are two views taken at right angles to each other and illustrating a further development of the invention.

Throughout the drawings like parts are designated by similar reference characters.

In the drawings, 2 represents a former, 3 a stylus or tracer co-operating therewith and 4 is the wheel dressing tool the movement of which in dressing the operative face of the grinding wheel to the required form is controlled by the former 2.

In the arrangement shown in Figures 1, 2, 3 and 4 the former 2 is fixed while the stylus 3 is carried by the long arm 5 of a lever—pivoted at 50 6 in the upper side of a saddle 7 having a rectilinear movement upon a fixed frame 8 in the direction of the length of the said former.

The short arm 9 of the lever engages a block 10 adapted to slide in a longitudinal groove 11 55

- in the upper side of a drum 12 which is free to rotate on ball bearings 13 at each end of a central spindle 14. The said spindle is also free to rotate and is mounted upon ball bearings 15 in the fixed frame 8. The block 10 is maintained in close relationship with the groove by means of springs 16 and has pivoted to it a pin 17 which projects into a hole in the end of the short arm 9 of the lever (see Figure 2A).
- 10 The saddle 7 embraces the drum 12 and spindle 14 and is fitted on the underside with an internally directed projection 18 engaging a helical groove 19 formed in the underside of the said spindle.
- 15 The drum is slotted at the underside as shown in Figure 4, to permit the said projection 18 to engage with and move along the helical groove 19 in the spindle and is formed with a groove 20 to receive a block 21 similar to the block 10. This block 21 is carried by one arm 22 of a bell crank lever journaled in a fixed part of the frame 8. The other arm of this lever carries a pin 24 at its free end engaging a groove 25 in one member 26 of a compound slide carrying the dressing tool 4. The other member 27 of the compound slide has a V rib and groove engagement 28 with a fixed part of the frame 8 and is adapted to be reciprocated in a direction at right angles to that of the first member by means of a toothed sector 29 on the end of the spindle 14 engaging a rack 30 on the slide member 27, as shown in Figure 3.
- In this construction the wheel dressing attachment occupies a position on the machine with the length of the former at right angles to the axis of the grinding wheel and the operation of the mechanism is such that as the operator, by means of a knob 5^a on the lever 5, moves the stylus 3 along and in contact with the former 2, the saddle 7 moves along the frame 8 and at the same time the lever has a rotary movement about its pivot 6 as the stylus follows the contour of the former. The movement of the stylus in the direction of the major median line of the former is transmitted by the saddle 7 to the spindle 14, the engagement of the projection 18 with the helical groove 19 therein, causing the said spindle to be turned about its axis to an extent which is determined by the lead of the helical groove and the longitudinal position of the saddle at any moment. This rotary movement of the spindle is imparted to the member 27 of the compound slide by means of the toothed sector 29 and rack 30 thereby causing the slide 26 as a whole, and hence the dressing tool 4, to have a traversing movement across the face of the wheel at a reduced ratio to that of the corresponding movement of the stylus. At the same time the rotary movement of the stylus, about the axis of the lever in the direction of the depth component of the former 2 is transmitted by the short arm 9 of the lever at a suitably reduced ratio to the rotatable drum 12 by means of the block 10. The resulting rotary movement of the drum is in turn transmitted to the arm 22 of the bell crank lever by means of the block 21, the other arm 23 operating by means of the pin 24, to give the slide member 26 a reciprocatory movement relatively to the slide member 27 towards and away from the axis of the grinding wheel corresponding with, but at a reduced ratio to, the movement of the stylus in the direction of the depth component of the former 2. The simultaneous rectilinear movements of the slide members 26, 27 are therefore such as to cause

the dressing tool 4 to reproduce in the wheel on a smaller scale the profile of the former. Any small departure from complete facsimile reduction which may occur in the nature of a slight curvature of the flanks of the ribs on the wheel can be corrected, either by suitable modification of the profile of the former, or, by the use of a similar rectilinear and rotary combination for the dressing tool.

For example, in the construction shown in Figures 5, 6, 7 and 8 the dressing tool holder 31 is carried by a spindle 32 which is journaled in a bearing 33 in a slide 34, the dressing tool 4 being off-set from the axis of said spindle. The rotary component of the combined movement of the stylus 3 is in this case reproduced on a smaller scale at the dressing tool 4 by means of the lever 5, 9 and the drum 12, an arm 35 on the spindle 32 engaging a block 21 engaging a groove 29 in the underside of the drum. At the same time the rectilinear movement of the stylus is reproduced on a reduced scale at the dressing tool by means of the saddle 7 and spindle 14 the latter being provided with a screw 36 engaging a nut 37 carried by the slide 34. In this construction the wheel dressing attachment occupies a position on the wheel with the length of the former parallel with the axis of the grinding wheel.

In either of the above described mechanisms both components of the combined movement of the stylus may be reduced to an equal extent at the dressing tool. For example in the arrangement shown in Figure 2, the relative dimensions of the arms of the lever carrying the stylus may be 5:1 and those of the bell-crank 22, 24 lever operating the compound slide 26, 27 carrying the dressing tool may be 3:1 thus giving an overall reduction of the rotary component of the combined movement of the stylus of 15:1. In the arrangement shown in Figures 5 to 8 the ratio of the arm 35 and the amount the dressing tool 4 is off-set from the axis of the spindle would in this case also be 3:1.

In the arrangement shown in Figure 2 the lead of the helical groove 19 in the spindle 14 and the pitch circle diameter of the toothed sector, or in the arrangement shown in Figure 6 the pitch of the screw 36 as the case may be can, if desired, also be chosen to give the dressing tool a 15:1 reduction in the rectilinear component of the combined movement of the stylus.

In order, however, to facilitate the free movement of the stylus over the former the reduction of the rotary motion of the stylus may be less than in the case of the rectilinear motion. Thus if the ratio of the arms of the bell crank lever aforesaid is 2:1 the former should have the depth of its profile reduced to two thirds of the value it would have if the ratio were 3:1. For example, if it is required to produce a thread form having an included angle of 55°, the included angle of the profile of the former for a 2:1 reduction will require to be increased to 75°, 58', thus giving a flatter profile and facilitating the traverse of the stylus over the former.

The stylus may be power operated in which case, as shown in Figure 6, the saddle 7 carrying the lever 5, 9 may be moved along the frame 8 by means of a lead screw 38, the stylus 3 being held in engagement with the former 2, so as to follow the profile thereof, by means of a spring 39 carried by the saddle and bearing against the short arm 9 of the said lever.

The lead screw may be rotated by means of an 75

electric motor or in any other suitable manner and has one end rotatably mounted in the frame 8 so as to be axially immovable therein while the free end works in a nut 40 carried by the saddle.

5 In a further development of the invention the construction of the improved wheel dressing apparatus is considerably simplified, the dressing tool being carried directly by the short arm of the lever. The apparatus, as shown in Figures 9 and 10, comprises two displaceable slides 41, 42 mounted in a common guide 43 and provided with means such as the differential screw 44, for traversing them along the guide with a given ratio of relative displacement. The slide 41 carries the lever in the long arm 5 of which the stylus or tracer 3 is mounted, whilst the short arm 9 carries the dressing tool 4. The slide 42 carries the former 2 which is an enlarged replica of the form it is required to dress. The ratio 10 of the lengths of the arms of the lever and of the displacements of the two slides will depend upon the degree of reduction required at the dressing tool in each case. In the example shown this ratio is 10:1. That is to say, the former is ten times the size of the form to be dressed, the arm 5 of the lever is ten times the length of the arm 9, and the movement of the slide 42 is ten times that of the slide 41. Any other desired ratio may, however, be adopted. The rectilinear component 15 of the combined movement of the dressing tool is given by the displacement of the slide 41, while the rotary component is given by the relative movements of the lever and former. Where the slides are operated by means of a differential screw, as shown, the dressing operation is carried out by rotating the screw which in the case of a 10:1 reduction will have four threads per inch at the part engaging the slide 42 and forty-four threads per inch at the part engaging the slide 41. A biasing spring 45 secured to the slide 41 and acting on the lever serves to maintain the stylus in contact with the former.

It is to be understood that any other suitable means than a differential screw may be employed 20 for moving the slides 41 and 42.

45 The invention in any of the forms above described is equally applicable to the dressing or forming of grinding wheels of the kind described in British Patent No. 216,507 in which the grinding wheel has a plurality of annular serrations or cutting edges of progressively increasing size, and to the dressing or forming of grinding wheels 50 of the kind described in British Patent No. 239,859 in which the grinding wheel has a plurality of annular grinding serrations or cutting edges so formed thereon as to provide spaces between the grinding wheel and the convolutions of the threaded member.

We claim:—

60 1. Apparatus for dressing the operative face

of a grinding wheel, comprising a former, a lever, a stylus carried by one arm of said lever and adapted to co-operate with said former, a slide carrying said lever and capable of rectilinear motion, a dressing tool and means operated by the slide and the other arm of said lever whereby the movement of the stylus in traversing the former is transmitted at a reduced ratio to the dressing tool.

2. Apparatus for dressing the operative face 10 of a grinding wheel, comprising a former, a lever, a stylus carried by one arm of said lever and adapted to co-operate with said former, a saddle carrying the lever and having a rectilinear motion, a dressing tool and a compound slide carrying said tool, one member of said slide being movable in one direction at a reduced ratio by the rectilinear motion of the saddle and the other member of said slide being simultaneously movable in another direction at a reduced ratio by 15 the other arm of said lever.

3. Apparatus for dressing the operative face 20 of a grinding wheel, comprising a former, a lever, a stylus carried by one arm of said lever and adapted to co-operate with said former, a saddle 25 carrying the lever and having a rectilinear motion, a dressing tool and a compound slide carrying said tool, a drum adapted to be turned about its axis by the other arm of said lever and to move one member of said slide at a reduced ratio 30 in one direction, and means operated by the rectilinear motion of the saddle to move the other member of said slide at a reduced ratio simultaneously in another direction.

4. Apparatus for dressing the operative face 35 of a grinding wheel, comprising a former, a lever, a stylus carried by one arm of said lever and adapted to co-operate with said former, a saddle carrying the lever and having a rectilinear motion, a dressing tool and a compound slide carrying said tool, means operated by the other arm 40 of said lever for moving one member of said slide at a reduced ratio in one direction and a spindle adapted to be turned about its axis by the rectilinear motion of the saddle for moving the other 45 member of the slide at a reduced ratio simultaneously in another direction.

5. Apparatus for dressing the operative face of a grinding wheel comprising a former, a lever, a stylus carried by one arm of said lever and adapted 50 to co-operate with said former, a slide carrying the lever, a slide carrying the former, a dressing tool operated by the other arm of said lever, and means for imparting a differential rectilinear motion to said slides whereby the 55 movement of the stylus is reproduced on a reduced scale by the dressing tool.

HERBERT HENRY HARLEY.
JAMES YORSTON.
